UNITED STATES PATENT OFFICE

143,433

DESIGN FOR AN ANIMATED EYE EXERCISER

Aubrey B. Leech, Los Angeles, Calif.

Application September 5, 1944, Serial No. 115,197

Term of patent 14 years

(Cl. D57—1)

To all whom it may concern:

Be it known that I, Aubrey B. Leech, a citizen of the United States of America, residing in the city of Los Angeles, county of Los Angeles, State of California, have invented a new, original, and ornamental Design for an Animated Eye Exerciser, of which the following is a specification, reference being had to the accompanying drawings forming a part thereof.

Fig. 1 is a front elevational view of an animated eye exerciser showing my new design as the same appears when it is not illuminated.

Fig. 2 is an enlarged front elevational view of the upper portion of the device when the same is illuminated from within and animated.

Fig. 3 is a side elevational view of the device.

Fig. 4 is a side elevational view of the device partly in section with the protective housing shown in Fig. 3 removed, showing the electric lamp for illuminating the lower portion of the

design, and the lamp base and one of the cylindrical rotating screens for illuminating and animating the upper portion of the design.

Fig. 5 is a sectional view in front elevation of the upper portion of the device taken on the line 5—5 of Fig. 4, showing the intermediate plate which cooperates with the rotating screen to produce an animated design on the upper portion of the forward plate of the device, and

Fig. 6 is a top plan view of the device showing the fins on top of the rotating screens which cause the screens to rotate in opposite directions in response to warm air currents passing upwardly therethrough from their respective lamps.

The dominant feature of my design resides in the upper portion thereof as illustrated in Fig. 2.

I claim:

The ornamental design for an animated eye exerciser, substantially as shown and described.

AUBREY B. LEECH.
